DRAFT RIGGING

Donald S. Barrows, Rochester, N. Y., assignor to
The Symington Company, New York, N. Y., a
corporation of Maryland

Application August 15, 1927, Serial No. 213,144

39 Claims. (Cl. 213—69)

This application is a continuation, in part, of my co-pending application Serial No. 72,303, filed November 30, 1925, now Patent No. 1,852,143, of April 5, 1932.

5 This invention relates to draft rigging and, more particularly, to a swivel butt coupler so designed and modified that it may be used with an A. R. A. integral striking casting and carry iron.

10 The principal object of my invention, generally considered, is the provision of a swivel butt coupler of the type involving a swivel block pivotally connected to the butt thereof, said butt being reduced in height by the elimination of the usual top and bottom lugs adapted to cooperate with corresponding webs or flanges on the swivel block, whereby the height of said butt is reduced to approximately that of a rigid shank coupler, thereby adapting it for employment with A. R. A. or standard integral striking casting and carry iron.

15 An object of my invention is the provision of a draft rigging involving a yoke, swivel butt coupler with a swivel block pivotally connected thereto and a horizontal key connecting said coupler and yoke, employed with a combined striking casting and carry iron, the butt of said coupler, when the swivel block is disconnected therefrom, being reduced in height by the elimination of the usual top and bottom bearing lugs so that it may be inserted in place with respect to the combined casting before the application of the wear plate thereto, said coupler butt being connected with the swivel block subsequent to insertion in place.

20 Another object of my invention is the provision of a swivel butt coupler in which the butt thereof is pivotally connected with an associated swivel block by means of an upright or vertical pin, said pin being formed for bottom removal and provided with bottom locking means such as a cotter, whereby connection between said coupler and swivel block may be made after said members are in place.

25 A further object of my invention is to provide a draft rigging involving a swivel butt coupler and an integral striking casting and carry iron with a readily removable wear plate on said carry iron, whereby the stem of the coupler may be inserted in place before application of the wear plate, after which said wear plate is positioned and connected to said carry iron.

30 Other objects and advantages of the invention relating to the particular arrangement and con-

struction of the various parts will become apparent as the description proceeds.

Referring to the drawings illustrating my invention, the scope whereof is defined by the appended claims:

5 Figure 1 is a plan of my swivel butt coupler, the associated combined striking casting and carry iron being illustrated in horizontal section with parts of the draft rigging diagrammatically designated in dot and dash lines.

10 Figure 2 is a side elevation of a portion of the coupler, the combined striking casting and coupler carry iron as well as other portions of the coupler being shown in central vertical section.

15 Figure 3 is a fragmentary front elevation of the combined striking casting and coupler carry iron, the removable wear plate being shown partly in vertical section.

20 Figure 4 is a plan of another embodiment of my invention, utilizing a vertical yoke, and shown partly in section.

25 Figure 5 is a vertical longitudinal sectional view on the line 5—5 of Figure 4 looking in the direction of the arrows.

30 Figure 6 is a horizontal sectional view of the vertical yoke shown in Figure 5 on the line 6—6 thereof looking in the direction of the arrows.

35 Figure 7 is a partial transverse sectional view on the line 7—7 of Figure 6 looking in the direction of the arrows.

40 Figure 8 is a fragmentary vertical longitudinal sectional view corresponding to Figure 5 but showing another modification.

45 Figure 9 is a fragmentary vertical transverse sectional view on the line 9—9 of Figure 8 looking in the direction of the arrows.

50 Referring to the drawings in detail, like parts being designated by like reference characters and first considering the embodiment of my invention illustrated in Figures 1, 2 and 3, there is shown a coupler 1 of the swivel butt type with the stem or shank portion 2 thereof extending through the coupler receiving aperture 3 of a combined striking casting and coupler carry iron 4. Said combined casting involves a striking portion 5, side portions 6, and a sill tie member or coupler carry iron portion 7 connecting the lower ends of the side portions 6. The side portions 6 are preferably formed with rearwardly extending flanges or webs 8, slotted at 9 so as to adapt them to serve as the forward portions of cheek plates which reinforce the sills 10 of the associated railway vehicle to which the flanges 8 are connected by rivets or other connecting means 11. In the present embodiment, although

the connecting webs 8 serve merely as the forward portions of cheek plates, the rear portions thereof being indicated diagrammatically by dot and dash lines at 12, it is obvious that I do not 5 wish to be limited to this showing. The sills 10 are slotted as indicated at 13 for receiving a draft key 14.

Extending rearwardly from the striking portion 5 of the combined striking casting 4 is a 10 horizontal web or shelf portion 15, said portion being preferably offset downwardly adjacent to its rear end as indicated at 16 in order to underlie the associated cover plate (not shown) to which it is adapted for connection. The top of 15 the offset portion 16 preferably corresponds with the top of the sills 10, the upper portion of said sills being coped as indicated at 17 to receive said web portion 16. Framing the opening 3 through the combined casting 4 is a horizontal 20 web or flange 18. For reinforcing the casting and strengthening the rearwardly extending web portions 15 and 16, a plurality of longitudinally extending vertical webs 19 are preferably provided, the rear ends of which taper and eventually merge into the rear end of the web 16.

The side portions 6 of the combined casting 4 are preferably angular in section as illustrated for providing the desired strength and the connecting coupler carry iron portion 7 in the embodiment disclosed is formed inverted U-shape in cross section with an upper web 20 and depending flanges 21 on opposite sides thereof, said flanges preferably increasing in depth towards the center thereof as illustrated particularly in 35 Figure 3. Positioned upon said carry iron portion 7 is a wear plate 22 which is formed for ready insertion or removal while the coupler is in position. For that purpose, it comprises a web portion 23, a rear flange portion 24 relatively deep, a front flange portion 25 relatively shallow and a pair of lugs or bendable tangs 26 on either side of said shallow flange portion 25. When it is desired to insert or remove the wear plate 22, the bendable tangs are positioned, as 40 indicated by dot and dash lines in Figure 2, so as to extend horizontally and thereby not interfere with the positioning or removal of the wear plate, the flange portion 25 being so shallow that it does not prevent insertion or removal 45 of the plate 22 even when the coupler is in position as illustrated. To apply the wear plate after insertion in place, the bendable tangs 26 are bent downwardly from the position indicated in dot and dash lines to that indicated in full lines where they serve to securely hold said plate 50 in position. In order to facilitate manufacture and minimize waste, the rear flange 24 of the wear plate 22 may be notched at its ends as indicated at 27, the amount of said notching corresponding to the difference between the depth 55 of the tangs 26 and the flange 25 so that the front of the blank for a wear plate may be cut simultaneously with the rear of an adjacent blank as will be understood.

60 The rear end of the shank 2 of the coupler 1 is pivotally connected to an auxiliary swivel block portion 28 by means of a pivot pin 29, the coupler shank, swivel block and pin being correspondingly slotted or notched as indicated at 30 65 to receive the draft key 14 for operatively connecting said coupler to an associated yoke 31. The rear face of the swivel block 28 is adapted to engage cushioning mechanism 32 indicated diagrammatically by dot and dash lines. In the 70 present embodiment, the yoke is shown of the

horizontal type but, as will be explained later, I am not necessarily limited to using a horizontal yoke.

The butt portion of the coupler or rear end of the stem 2 thereof is provided with rearwardly extending horizontal web or flange portions 33, said portions being curved along the rear faces or edges thereof coaxially with respect to the pivot pin 29, said pivot pin passing through registering apertures 34 therein. The 10 swiveling block or auxiliary portion 28 is provided with forwardly extending web or flange portions 35, 36 and 37 which closely interengage the web portions 33 of the coupler and form pockets 38 therebetween for operatively engaging the curved edges of the flanges or webs 33 of the coupler. These pockets 38 are preferably formed with bearing surfaces coaxial with the pivot member 29 for proper swiveling engagement with respect to the portions 33 of the 20 coupler.

The flanges or webs 35 and 37 of the swivel block are preferably curved at their forward edges but are not adapted to engage correspondingly curved portions on the coupler stem, 25 such portions being purposely omitted to give a stem of relatively small height whereby the same is readily inserted and removed through the aperture 3 in the combined casting 4. The central or intermediate flange 36 on the swivel 30 block, which is intersected by the way or slot 39 for the key 14, is likewise formed with coaxially curved edges 39 for cooperation with the correspondingly curved pocket portions 40 on the stem of the coupler. That portion of the 35 swivel block rearwardly of the pivot pin 29 may be cored out as indicated at 41 to minimize weight.

The pin 29 is retained in position not only by the key 14 which intersects the same but also 40 by a cotter 42 passing through depending lugs 43 on the swivel block and engaging a notched portion 44 on the pin. Upward movement of the pin is, in the embodiment disclosed, limited by a corresponding cotter 45 extending through 45 registering apertures in a U-shaped boss 46 and overlying a portion of the pin 29. By making the boss U-shaped as illustrated, the strength thereof is increased and the locking cotter is protected.

50 When it is desired to apply the coupler and swivel block to the car, the procedure is desirably as follows. The yoke is first placed in position on the rear guides (not shown) and the point of the key 14 inserted to hold it in place. 55 The swivel block 28 is positioned between the arms of the yoke, the key being moved a little further in order to support the block but not enough to cover the pin hole therethrough. The coupler stem or shank is then inserted through 60 the aperture 3 in the combined casting, into place between the arms of the yoke with the flanges or webs 33 inserted in the corresponding pockets 38 in the swivel block. The pin 19 is then inserted from the bottom and the supporting cotter 42 applied. It will be obvious that the top cotter 45 may be in position initially. The draft key 14 is then driven all the way through to normal position. The carry iron wear plate 22 is then applied from the rear 70 beneath the stem of the coupler and the tangs 26 bent down to lock the same in place as illustrated.

When it is desired to remove the coupler, the coupler head is first jacked up and the wear 75

plate taken out after bending the tangs 26 up to inoperative position. The bottom cotter 42 is then removed and the draft key taken part way out allowing the pin 29 to fall out. The 5 coupler may then be entirely removed and the key 14 further withdrawn until the swivel block 28 is freed permitting removal of said block. The key now holds the yoke in position ready for the application of a new coupler.

10 Referring now to the embodiment of my invention illustrated in Figures 4 to 7, inclusive, a coupler 1^a is illustrated having a stem or shank 2^a which may be identical with that of the first embodiment. The combined casting 4^a, illustrated diagrammatically, may also be identical 15 with that of the first embodiment and be connected to sills 10^a as previously described. My coupler, in the present instance, is shown employed with a yoke 31^a of the vertical type, the draft key 14^a extending through a hooded portion 47 on said yoke and passing through corresponding slotted portions in the stem 2^a of the coupler, the swivel block 28^a and the pin 29^a. The swivel or butt block 28^a, which can be considered 20 as completing the coupler shank and the key slot therein, may be very similar to the swivel block 28 of the first embodiment except that the fastening means 45 and U-shaped boss 46 therefor at the top are dispensed with, vertical 25 movement of said pin 29^a being limited by the top arm of the yoke 31^a. The lower web or flange 37^a of the swivel block 28^a is shown provided with a pair of depending apertured lugs 43^a between which extends a cotter 42^a, said cotter, 30 however, passing through a central notch 44^a in the key rather than an eccentric notch as in the first embodiment.

35 The upper and lower arms of the yoke 31^a are preferably formed with, respectively, depending and upstanding shoulders 48 and 49 which are preferably curved coaxially with respect to the pivot pin 29^a, the forward faces of the upper and lower flanges 35^a and 37^a of the swivel block being correspondingly curved, thereby permitting equalizing between said swivel block and the yoke and serving as a connection, auxiliary to the key 14^a, between the swivel block 28^a and the yoke 31^a. In case either the connection at the shoulders 48 and 49 or the key 14^a should fail, the other would, in such an emergency, act 50 to transmit the entire draft forces from the coupler.

55 The lower arm of the yoke 31^a is formed with a depressed or downwardly offset portion 50 providing for rearward motion of the swivel block and particularly the lugs 43^a thereon with respect thereto. Said depressed portion 50 is cut away at its central portion as indicated at 51 to facilitate application of the pin 29^a. 60 The sides 52 of the yoke form the hooded portion connecting the ends of the upper and lower arms thereof and are slotted as indicated at 53 for receiving the key 14^a. In order to permit the desired relative movement between 65 the coupler and yoke on buff, the slots 53 are longer than the key 14^a and the slot 30^a through the coupler is likewise lengthened forwardly so that the combined excess lengths of the slots 53 and 30^a provide for the necessary rearward 70 motion of the coupler. The depressed portion 50 of the yoke is extended not only to permit the desired motion of the coupler but also to facilitate assembly of the swivel block and coupler with respect thereto. In order to 75 provide for supporting the associated front fol-

lower 55 and the forward portion of the cushioning mechanism 56, indicated diagrammatically by dot and dash lines, at the desired elevation, the depressed portion 50 is preferably bordered by ribs or flanges 54, the upper surfaces of which are on a corresponding level with that of the main portion of the lower arm of the yoke 31^a.

10 In operation, the present embodiment of my invention is used with stop lugs 57 indicated diagrammatically by dot and dash lines, said lugs being connected to the sills in any usual or desired manner as will be understood. The present form of my invention is adapted to be applied to and used with the same form of combined striking and coupler carry iron casting as specifically described in connection with the first embodiment and the operation and mode of connection and detachment of the parts may correspond with that of the first embodiment 15 except that the inherent differences between horizontal and vertical yokes are involved. It should also be noted that the relative rearward motion of the coupler with respect to the yoke in the present embodiment is provided mainly by increasing the length of the slot in the coupler rather than by correspondingly increasing the length of the slot in the yoke. The swivel butt may be inserted in position 20 between the arms of the yoke beyond the hooded or side portions 52 thereof with the depending lugs 43^a passing behind the rear ends of the ribs 54 at the depressed portion of the lower 25 arm of the yoke.

30 Referring now to the modification of my invention illustrated in Figures 8 and 9, a construction is shown which corresponds in some respects to that disclosed in Figures 4 to 7, inclusive, in that it involves a vertical yoke 31^b provided with a lower shouldered portion 49^b and an upper shouldered portion, not shown, corresponding to the shouldered portions 49 and 48 of the previous modification, which portions cooperate with the swivel block 28^b which may correspond substantially with the swivel block 28^a of the previous modification except that it is formed without the depending lugs 43^a which receive locking means 42^a. Said swivel block, as in the previous embodiments, co-operates with the butt portion of the coupler 1^b in the same manner as previously described and is swiveled thereto by means of an upright pin 29^b.

35 Instead of holding the pin 29^b in place by locking means extending beneath the same and connected to the lower flange or web 37^b of the swivel block 28^b, said locking means 42^b is connected to the lower arm of the vertical yoke 31^b, and preferably extends through an aperture 55 beneath the lower end of said pin 29^b, 40 the ends of said locking member or cotter 42^b being bent downwardly, as indicated at 56, to lock the same in place. In order to provide for insertion and removal of the pin 29^b while the swivel block and coupler are assembled with the yoke, the lower arm of said yoke is provided 45 with an aperture 51^b through which said pin is inserted from below, said aperture being substantially closed by the cotter 42^b to lock said pin in place. In order to provide for the necessary longitudinal movement of the coupler, swivel block and pin with respect to the yoke 31^b, a slot 57 is provided in the lower arm of said yoke which slot need only be the approximate width of the pin 29^b and in length need 50 55 60 65 70 75

- only be sufficient to permit the normal relative travel between the coupler and yoke.
- The modification of my invention just described avoids the disadvantage of offsetting the lower arm of the yoke 31^b downwardly to the extent necessary in the previously described modification illustrated in Figures 4 to 7, inclusive, as it will be obvious that with such an offset a high local bending moment is produced in the lower arm of the yoke, making it necessary to strengthen said arm by additional metal which serves no other purpose. By providing the locking member or cotter 42^b connected to the yoke instead of the swivel block the necessity of an offset is practically eliminated inasmuch as the amount of offset provided and indicated at 58 is almost negligible and all that is required is a sufficient offset to compensate for the shallow groove 57 previously described. Except as specifically described in connection with the present embodiment the same may correspond substantially with that of the embodiment illustrated in Figures 4 to 7, inclusive.
25. From the foregoing, it will be apparent that I have devised a swivel butt coupler which is so modified that it may be used with an A. R. A. integral striking casting and carry iron, the butt or stem of said coupler being formed of reduced height so that it may be inserted in place through the aperture in such integral casting before application of the swivel block. This has been accomplished not only by eliminating top and bottom lugs which previously have been used on the shank of the coupler, but by also providing a wear plate which is adapted for insertion or removal with respect to the carry iron portion of the casting while the coupler is in position. It will be apparent that, as contra-distinguished from previous forms of swivel butt couplers, it is necessary to remove the swivel pin as well as the draft key in order to remove the shank of the coupler. It will also be apparent that my invention is not limited to use with any particular type of yoke and may be employed equally well with those of both horizontal and vertical types.
- Having now described my invention, I claim:
1. In a draft rigging, in combination with a vertical yoke, an articulated coupler, an upright pin intersecting the elements of the articulated coupler for pivotally connecting them, a key intersecting the elements of said coupler, pin and yoke for holding said members in operative relation, the upper arm of the yoke limiting upward movement of said pin, and locking means extending below one of the elements of said articulated coupler and said pin for limiting downward movement of the latter.
  2. In a draft rigging, in combination with a yoke, a coupler of the swivel butt type formed with rearwardly extending flanges on the inner end thereof, a swivel block associated with said flanges on the coupler and formed with corresponding intercalated flanges embracing said coupler flanges, means extending through said intercalated flanges on the members for pivotally connecting the same, a key extending through registering slotted portions on the yoke and coupler parts for operatively connecting said coupler and yoke, said yoke being formed with shouldered portions extending forwardly of the upper and lower flanges on the swivel block as auxiliary means for connecting said coupler and yoke.

3. In a draft rigging, in combination with a coupler, a swivel block formed with webs embracing the butt of said coupler, means passing through corresponding apertures in said webs and coupler butt for pivotally connecting the same, a yoke with a hooded portion embracing said swivel block and the butt portion of the coupler, means depending from said swivel block for locking the pivotal means in place, the lower element of said yoke being formed with a depressed portion receiving said locking means and permitting relative motion therebetween, and ribs formed on either side of said depressed portion to provide a support for the forward portion of associated draft gear.

4. In railway draft rigging, a vertical yoke, a coupler stem received in the forward portion of said yoke for relative longitudinal movement, a swivel block with webs embracing the rearward portion of said stem, and means extending through said webs and stem for pivotally connecting the parts, said yoke having shouldered portions provided on its upper and lower arms overlying the forward edges of said webs for limiting relative movement between said coupler stem and yoke.

5. In railway draft rigging, a vertical yoke, a coupler stem received between the arms of said yoke for relative longitudinal movement, a swivel block associated with the rear portion of said stem, a pivot pin connecting said stem and swivel block, and means depending from said swivel block for locking said pivot pin in place, the lower arm of said yoke being downwardly offset below said depending means to provide clearance and permit relative motion therebetween, and ribs upstanding from said yoke on either side of said depending means with their tops flush with the normal level of the lower arm of the yoke and adapted to support the forward portion of associated cushioning mechanism.

6. In railway draft rigging, in combination with a vertical yoke, a coupler stem associated therewith, a swivel block embracing the rearward portion of said stem, and a pin pivotally connecting said swivel block and stem and terminating short of said yoke, so that the stem and block move together independently of the yoke, the lower arm of said yoke being apertured to provide for insertion and withdrawal of said pin while the coupler and yoke are assembled, said aperture being normally operatively closed by retaining means connected to said yoke for holding the pin in place.

7. In railway draft rigging, the combination of a coupler, a yoke, and means for connecting said yoke and coupler, said means including a bearing block slidable relative to said yoke and engageable therewith for transmittal of draft forces, and means for pivotally securing said coupler to said block.

8. In draft rigging, the combination with a yoke member, of a coupler stem having a plurality of spaced arms adjacent its inner end, a block slidable in said yoke having arms embracing the arms of said coupler, a pivot pin for pivotally connecting said stem and block, means on said yoke adapted to have cooperative engagement with arms on said block in draft whereby said pin is subjected to quadruple shear.

9. In railway draft rigging, the combination of a yoke, a coupler associated with said yoke and having a two-part coupler stem movable

with respect to said yoke during transmission of buffing forces, means providing a pivotal connection between said parts, one of said parts having portions embracing the other, and means 5 engaging the ends of said portions for transmission of draft forces to said yoke.

10. In railway draft rigging, the combination of a yoke formed with bearing portions, a coupler associated with said yoke and having a two-part 10 part coupler stem movable with respect to said yoke during transmission of buffing forces, and means providing a pivotal connection between said parts, one of said parts having portions embracing the other, said bearing portions being 15 adapted to engage the ends of said embracing portions for transmission of draft forces of said yoke.

11. In draft rigging, the combination with a yoke member, of a coupler provided with a rearwardly open centrally disposed recess, a block adapted to slidably fit within said yoke member, a portion of said block being adapted to extend within said recess and other portions of said block embracing portions of said coupler, 25 means for pivotally connecting said block and coupler, and means for engaging said embracing portions of said block for transmitting strains to said yoke.

12. In a railway draft rigging, the combination with a yoke; of a coupler provided with a shank; a butt member swivelled to the shank and having an end abutment face adapted to engage the front follower of a railway draft rigging, said butt member and yoke having 30 shouldered engagement to effect movement of the yoke in unison with the coupler in draft; and a coupler key extending through a portion of the coupler and yoke, forming an emergency connection for the same.

13. In a railway draft rigging, the combination with a yoke; of a coupler provided with a shank completed by a butt member swivelled thereto, movable independently of the yoke on buff, and having an end abutment face adapted to engage 35 the front follower of a railway draft rigging, said butt member and yoke having shouldered engagement to effect movement of the yoke in unison with the coupler in draft; and a coupler key extending through the coupler shank and 40 yoke, forming a connection for the same.

14. In coupler mechanism, the combination of a coupler, a hooded yoke associated therewith for receiving a portion of said coupler, a bearing block, a pivotal connection between said 50 coupler and block, and bearing portions provided on the end portions of a pair of walls of said yoke and having engagement with cooperative bearing portions on said block to normally receive draft forces from said bearing block.

15. In railway draft rigging, the combination of a coupler, a hooded yoke, means pivotally and slidably connecting said yoke and coupler, said means including a bearing block embracing a portion of said coupler and pivotally connected 55 to said coupler, said embracing portion of said block contacting an abutment portion of said yoke in draft, whereby relative pivotal action between said coupler and bearing block is permitted to transmit draft forces to said yoke.

16. In railway draft rigging, the combination with a hooded yoke provided with bearing portions adapted to receive draft strains, of a coupler stem comprising a plurality of relatively 60 rotatable members, cooperating bearing portions provided on said rotatable members adapted to

transmit buffing strains to the draft rigging, other bearing portions provided on one of said rotatable members adapted to coact with the bearing portions on the yoke, and means for pivotally connecting said rotatable members. 5

17. In railway draft rigging, the combination with a hooded yoke provided with bearing portions adapted to receive draft stresses, of a two-part 10 coupler stem having portions thereof pivotally connected at a point intermediate the ends of said yoke member, means formed on one of the coupler portions for engaging an element of the draft rigging movable with respect to said yoke under movement in one direction, bearing surfaces on one of said coupler portions disposed about the pivotal connection thereof, some of said bearing surfaces being adapted to coact with the bearing portions on the yoke upon draft movement of said draft rigging. 15

18. In railway draft rigging, the combination 20 with center sills, of a swivel butt coupler having means for engaging a movable element of the draft rigging upon movement in one direction, a hooded yoke provided with bearing portions, certain of said bearing portions being adapted 25 to contact means carried by said sills to transmit draft stresses thereto, said yoke having other bearing portions adapted to receive draft stresses, a plurality of co-acting bearing portions provided on said coupler butt, some of said 30 bearing portions being adapted to coact with bearing portions on the yoke in draft.

19. A coupler butt adapted for slidable movement with respect to an associated hooded yoke including a plurality of pivotally connected 35 members, co-acting bearing portions provided on said members and arranged concentrically of said pivotal connection, and a bearing portion provided on at least one of said members, said bearing portion being adapted to engage a complimentary bearing portion on said associated 40 yoke for the transmission of draft forces.

20. In draft rigging, the combination of a hooded yoke provided with spaced arms, a coupler butt arrangement slidable with respect to 45 said yoke, said arrangement including a block having portions embracing the coupler shank, said yoke and portions having complementary draft-force-transmitting bearing surfaces.

21. In draft rigging, the combination of a 50 hooded yoke, a coupler butt arrangement slidable in said yoke and including a bearing block having portions embracing the coupler shank and a pivotal connecting pin extending uninterruptedly through said bearing block and shank 55 connecting said block and coupler shank, said portions and yoke having complimentary co-acting draft-force-transmitting bearing surfaces.

22. In draft rigging, the combination of a 60 hooded yoke, a coupler stem slidable in said yoke, said stem comprising a pair of sections, said sections having intercalated portions, and a pin extending uninterruptedly through said portions and adapted to pivotally connect said sections, 65 one of said sections and yoke having complementary co-acting bearing surfaces for the transmission of draft forces.

23. In draft rigging, the combination with a hooded yoke member having upper and lower 70 walls, of a two-part coupler stem movable with respect to said yoke having the portions thereof pivotally connected at a point intermediate the ends of said yoke member, a portion of one of said portions engaging a movable element of the 75

- draft rigging under movement in one direction, and a portion engaging a wall of said hooded yoke upon movement in the opposite direction for transmitting draft forces thereto.
- 5 24. In coupler mechanism, the combination of a hooded yoke having bearing members disposed thereon, a coupler associated with said yoke and movable with respect thereto, a bearing member pivotally connected to said coupler and movable therewith with respect to said yoke, means on said yoke for guiding said bearing member, said bearing member and coupler having complementary bearing faces engageable over a substantially constant area regardless of the relative position of said coupler and yoke, said bearing member having members engaging said first named bearing members for transmitting stresses to said yoke.
- 10 25. In railway draft rigging, the combination of a yoke, a coupler associated with said yoke and having a two-part coupler stem movable with respect to said yoke during transmission of buffing forces, means providing a pivotal connection between said parts, one of said parts having substantially horizontally disposed portions embracing the other, and means engaging the ends of said portions for transmission of draft forces to said yoke.
- 15 26. In railway draft rigging, the combination of a yoke formed with bearing portions, a coupler associated with said yoke and having a two-part coupler stem movable with respect to said yoke during transmission of buffing forces, and means providing a pivotal connection between said parts, one of said parts having substantially horizontally disposed portions embracing the other, said bearing portions being adapted to engage the ends of said embracing portions for transmission of draft forces to said yoke.
- 20 27. In railway draft rigging, the combination of a yoke, a coupler associated with said yoke and having a two-part coupler stem movable with respect to said yoke during transmission of buffing forces, one of said parts having portions embracing the other, and means associated with said parts and cooperating with said embracing portions providing a pivotal connection therebetween, said yoke and portions having complementary bearing surfaces for transmission of draft forces.
- 25 28. In railway draft rigging, the combination with a slotted coupler having a bearing surface, a slideable bearing block pivoted to said coupler, having a bearing surface cooperating with said first-named bearing surface, said bearing block having other bearing surfaces, and a hooded yoke cooperating with said coupler and having top and bottom walls provided with bearing surfaces cooperating with said last-named bearing surfaces for resisting draft forces.
- 30 29. In railway draft rigging, the combination with a coupler, of a yoke provided with a hooded end, means including a bearing block and a pin pivotally connecting said coupler and yoke, means carried by said yoke for retaining said pin in operative position, and means including coating bearing surfaces provided on said hooded end and said first-named means, said bearing surfaces being adapted to permit relative pivotal movement of the coupler and yoke when engaged as the result of movement of the draft rigging.
- 35 30. In railway draft rigging, the combination with a coupler provided with a bearing block having spaced bearing portions, of a yoke having a hooded end, one pair of walls of which is formed with slots for emergency reception of the standard key and the other pair of walls of which is provided with bearing surfaces adapted to be engaged by the spaced bearing portions of said block upon draft movement of said draft rigging, means for pivotally connecting said coupler and yoke, and a retaining member cooperating with said pivotal means and carried by said yoke.
- 40 31. In draft rigging, the combination with a yoke member, of a coupler stem having a plurality of spaced arms adjacent its inner end, a block slideable in said yoke having arms embracing, and an arm embraced by the arms of said coupler, a pivot pin for pivotally connecting the arms of said stem and block, and means on said yoke adapted to have cooperative engagement with arms on said block in draft, whereby said pin is subjected to quadruple shear.
- 45 32. In draft rigging, the combination with a yoke member, of a coupler provided with a rearwardly open centrally disposed recess, a block adapted to slidably fit within said yoke member, a portion of said block being adapted to extend within said recess and other portions of said block embracing portions of said coupler, means for pivotally connecting said block and coupler, and means for engaging said embracing portions of said block for transmitting stresses to said yoke.
- 50 33. In draft rigging, the combination of a yoke provided with spaced arms, a coupler butt arrangement slideable with respect to said yoke, said arrangement including a block having portions embracing the coupler shank, said yoke and portions having complementary draft-force-transmitting bearing surfaces disposed in spaced vertical relation.
- 55 34. In draft rigging, the combination with a yoke member, of a coupler stem comprising intermeshing members, means independent of said yoke member for pivotally connecting said intermeshing members intermediate the ends of said yoke, and means separable from and carried by said yoke member for retaining said connecting means in operative position.
- 60 35. In coupler mechanism, the combination of a hooded yoke having bearing members disposed thereon, a coupler associated with said yoke and movable with respect thereto, a bearing member pivotally connected to said coupler and movable therewith with respect to said yoke, means on said yoke for guiding said bearing member in a transverse direction, said bearing member and coupler having complementary bearing faces engageable over a substantially constant area regardless of the relative position of said coupler and yoke, said bearing member having members engaging said first-named bearing members for transmitting stresses to said yoke.
- 65 36. In a draft rigging, in combination with a vertical yoke, an articulated coupler, an upright pin intersecting the elements of the articulated coupler for pivotally connecting them, a key intersecting the elements of said coupler, pin and yoke for holding said members in operative relation, the upper arm of the yoke limiting upward movement of said pin, and locking means extending below one of the elements of said articulated coupler and said pin for limiting downward movement of the latter, one of said articulated coupler elements having a pair of lugs de-

pending therefrom and disposed on opposite sides of the lower portion of said pin and apertured to retainingly receive said locking means.

37. In railway draft rigging, in combination with a vertical yoke, a coupler stem associated therewith, a swivel block embracing the rearward portion of said stem, a pin pivotally connecting said swivel block and stem and terminating short of said yoke, so that the stem and block move together independently of the yoke, the lower arm of said yoke being apertured to provide for insertion and withdrawal of said pin while the coupler and yoke are assembled, and means normally operatively closing said aperture for holding the pin in place.
38. In a draft rigging, in combination with a coupler, a swivel block formed with webs embracing the butt of said coupler, means passing through corresponding apertures in said webs and coupler butt for pivotally connecting the same, a yoke with a hooded portion embracing said swivel block and the butt portion of the coupler, means depending from said swivel block for locking the pivotal means in place, the lower

element of said yoke being formed with an upwardly opening pocket, receiving said locking means and permitting relative motion therebetween, and portions on either side of said pocket to provide a support for the forward portion of associated draft gear.

39. In railway draft rigging, a vertical yoke, a coupler stem received between the arms of said yoke for relative longitudinal movement, a swivel block associated with the rear portion of said stem, a pivot pin connecting said stem and swivel block, and means depending from said swivel block for locking said pivot pin in place, the lower arm of said yoke having an upper surface downwardly offset, along the longitudinal center line thereof, below said depending means to provide clearance and permit relative motion therebetween, and portions on either side of said depending means with their tops lying in the plane of the lower arm of the yoke for supporting the forward portion of associated cushioning mechanism.

DONALD S. BARROWS.
